UNITED STATES PATENT OFFICE.

JOHN SHIRLEY HOWKINS, OF THORNTON HEATH, ENGLAND.

DEVICE FOR SUPPORTING THE UNDER PART OF THE FOOT.

SPECIFICATION forming part of Letters Patent No. 689,080, dated December 17, 1901.

Application filed August 5, 1901. Serial No. 70,992. (No model.)

To all whom it may concern:

Be it known that I, JOHN SHIRLEY HOWKINS, engineer, a subject of the King of Great Britain, residing at 45 Beulah Road North, 5 Thornton Heath, county of Surrey, England, have invented certain new and useful Improvements in Devices for Supporting the Under Part of the Foot, of which the following is a specification.

10 This invention relates to devices intended for supporting the arch of the foot, and has reference more particularly to a built-up metallic spring-plate intended to be strapped onto the foot or to be fitted in the sole of the 15 boot and curved to fit the arch of the foot.

A feature of the invention is the special arrangement hereinafter described for obtaining a high degree of elasticity especially along the inner half of the device—*i. e.*, the part 20 corresponding to the hollow side of the foot.

The invention will be readily understood by reference to the accompanying drawings, in which—

Figure 1 is a plan of one form of the device. Fig. 2 is an edge view of the same. Fig. 3 is an illustrated perspective view. Fig. 4 illustrates the way the device is built up and shows an end view of the three leaves or plates separated.

30 *a*, *b*, and *c* are three thin resilient leaves or plates of steel which have teeth cut in them on one side and are bent to the required form and then tempered. The teeth *a'* *c'* of the top and bottom leaves or plates *a* and *c* slant 35 in opposite directions, so as to cross or interlace with each other, while the teeth *b'* of the intermediate plate are shortened and are straight—*i. e.*, they do not slant.

The device has a slight sweep or curvature 40 in the direction of its length and a somewhat sharper bend following the line *xx*, Fig. 1, which produces a hollow in the upper side well adapted to fit comfortably into the arch of the foot.

45 The fact of the inner half of the device having the interlacing teeth, as shown, imparts a great degree of elasticity under that side of the foot where the yielding tendency is greatest. Moreover, this elasticity is very 50 evenly graduated, since near the line *xx* the support is given by all three sets of teeth, while toward the edge only the two interlac-

ing sets act. Moreover, it will be seen that the teeth overlap in a particular way, the tooth at the heel end (the lower part of Fig. 1) overlapping the next, and so on. Thus the pressure which usually starts at the heel is transmitted from tooth to tooth along the whole series. It will be seen that the tips of the longer teeth form a practically continuous line and constitute the inner edge of the device.

The perspective view, Fig. 3, shows very clearly the general contour of the support. This figure is not intended to illustrate the arrangement of the teeth, which is clear from Fig. 1, and hence these are only partially indicated.

It should be understood that single plates with straight teeth may be used to form the device, if desired, although the spring-plates with teeth are preferred. Furthermore, the support may be strengthened when required by suitable reinforcing leaves or plates, as may be found desirable.

75 The device is preferably held together by stitching *d*, passed through holes *e* and through the roots of the adjacent teeth, as shown. It may be provided with a covering *f*, of leather or any other suitable material, to 80 which light straps or bands—say of elastic—may be attached for the purpose of securing it to the foot. Such a covering and straps are indicated in Fig. 3.

What I claim, and desire to secure by Letters Patent of the United States, is—

1. In a device for supporting the under part of the foot, a plurality of superposed plates having teeth on their edges and said teeth being interlaced.

2. In a device for supporting the under part of the foot upper and lower plates having oppositely-inclined interlaced teeth and an intermediate plate having teeth interlaced with said other teeth.

3. In a device for supporting the under part of the foot the combination of thin superposed resilient plates, teeth on said plates arranged to interlace, and means for securing said plates together, substantially as described.

4. In a device for supporting the under part of the foot, the combination of thin superposed resilient plates, interlacing teeth on the

inner sides of said plates, means for holding said plates together, a covering to inclose said plates and straps to hold the device in position against the under side of the foot.

5. In a device for supporting the under part of the foot the combination of an upper resilient leaf or plate having teeth slanting one way, a similar lower plate having teeth slanting the other way and interlacing with the first, and a similar intermediate plate having short straight teeth substantially as described.
10. In a device for supporting the under part of the foot the combination of an upper and

lower resilient leaf or plate having interlacing teeth, an intermediate resilient plate having 15 shortened interlacing teeth, a covering for said plates, and straps or bands for holding them in position beneath the foot, substantially as described.

In testimony whereof I have hereunto set 20 my hand, in presence of two subscribing witnesses, this 25th day of July, 1901.

JOHN SHIRLEY HOWKINS.
